UNITED STATES PATENT OFFICE.

ERNEST GEORGE MITCHELL, OF BOWDEN, ENGLAND.

MEANS FOR FORMING ANNOUNCEMENTS ON GLASS WINDOWS AND OTHER PLANE SURFACES.

No. 846,043.

Specification of Letters Patent.

Patented March 5, 1907.

Application filed April 21, 1906. Serial No. 813,026.

To all whom it may concern:

Be it known that I, ERNEST GEORGE MITCHELL, a subject of the King of Great Britain, residing in Bowden, in the county of 5 Chester, in the Kingdom of England, chemist, have invented certain new and useful Improvements in Means for Forming Announcements on Glass Windows and other Plane Surfaces, for which application has 10 been made in Great Britain, No. 9,242, dated May 2, 1905.

This invention has for its object an arrangement whereby paper, celluloid, papier-mâché, and other like letters can be applied 15 to glass windows, boards, and other structures rapidly and effectively and without skilled labor, so as to produce a neat-looking advertisement or announcement.

In the accompanying drawings, Figure 1 20 is an elevation of letters made in accordance with the present invention. Fig. 2 is a side view, and Fig. 3 a detail, of a spacing-piece.

The invention consists, essentially, in stamping the letters out of the cardboard, 25 paper, or other material which has been gummed on one side, but leaving, as shown in the accompanying drawing, either on each side of the bottom or on each side of the bottom and top, a little strip or spacing-piece *a* 30 of the material beyond the letter, so as to show the exact rectangle occupied by the letter and half the spacing between the letters. The rectangle for the letter "S" is indicated by the dash-and-dot lines *C*, *D*, and *E* and the 35 base of the letter, and for the letter "L" by the lines *E*, *G*, and *F* and the base of the letter "L" from the line *E* to *F*. The lines *C*, *E*, and *F* are at the respective extreme limits of the 40 spacing-pieces, and the lines *D* and *G* are along the tops of the letters "S" and "L" respectively.

This extra little piece has preferably weakened lines, nicked or perforated, as at *a'*; so that it can easily be broken or torn off, and 45 has a resist *b*, such as tinfoil or other material, placed over the gum on it. The result is when a series of these letters each having the corners of a square are placed in a row they can be lined to a given line and be accurately spaced by simply being pressed up together. The gum can be moistened, and thus the letters stuck to the glass or board, and then when these have dried the squaring-pieces *a* at the corners can be torn or 50 broken off or cut off with a sharp knife, and thus a clearly-defined letter remains fixed to

the glass. These letters can be sent out in various sizes, various colors, and any required shape, and they can not merely be gummed, but they can have attached to 60 them adhesive cements, insoluble in water, but soluble in some other liquid—such, for instance, as spirits of wine or benzol. In that case the letters can be simply wet with benzol or spirits of wine instead of with 65 water when being placed in position. If the outer surface of the letters be waterproofed with a little celluloid solution, india-rubber solution, or the like, they will stand very permanently on a glass window when fixed with 70 pyroxylin solution or other solution as described to be insoluble in rain-water. Strips *c*, Fig. 3, of ungummed paper moistened are placed between letters where wider spacing is required and removed after the lettering is 75 complete.

I declare that what I claim is—

1. In means for forming announcements on glass windows and other plane surfaces, letters adapted to form the announcement, 80 and small strips or spacing-pieces connected to the same, said strips or spacing-pieces being of such a size as to indicate the exact rectangle occupied by the letter and half the spacing between the letters, and an adhesive 85 layer on the back of said letters.

2. In means for forming announcements on glass windows and other plane surfaces, letters adapted to form the announcement, 90 and small strips or spacing-pieces connected to the same, said strips or spacing-pieces being of such a size as to indicate the exact rectangle occupied by the letter and half the spacing between the letters, an adhesive layer on the back of said letters, and a resist 95 on the back of said strips.

3. In means for forming announcements on glass windows and other plane surfaces, letters adapted to form the announcement, 100 and small strips or spacing-pieces connected to the same, said strips or spacing-pieces being of such a size as to indicate the exact rectangle occupied by the letter and half the spacing between the letters, said strips having weakened lines so as to be easily removed. 105

4. In means for forming announcements on glass windows and other plane surfaces, letters adapted to form the announcement, 110 and small strips or spacing-pieces connected to the same, said strips or spacing-pieces being of such a size as to indicate the exact

rectangle occupied by the letter and half the spacing between the letters, said strips having weakened lines so as to be easily removed, adhesive means on the back of said letters and strips, and a resist on said strips.

5. In means for forming announcements on glass windows and other plane surfaces, letters adapted to form the announcement, and small strips or spacing-pieces connected to the same, said strips or spacing-pieces being of such a size as to indicate the exact rectangle occupied by the letter and half the

spacing between the letters, in combination with spacing-strips for use where wider spacing is required, an adhesive layer on the back 15 of said letters and spacing-pieces, and a resist on said spacing-pieces.

In witness whereof I have hereunto signed my name, this 10th day of April, 1906, in the presence of two subscribing witnesses.

ERNEST GEORGE MITCHELL.
